UNITED STATES PATENT OFFICE.

PERCY J. HINDMARSH, OF LINCOLN, NEBRASKA, ASSIGNOR TO THE AMERICAN STEEL & WIRE COMPANY OF NEW JERSEY, OF HOBOKEN, NEW JERSEY, A CORPORATION OF NEW JERSEY.

FENCE-POST.

1,224,927.

Specification of Letters Patent.

Patented May 8, 1917.

Application filed October 23, 1915. Serial No. 57,476.

To all whom it may concern:

Be it known that I, PERCY J. HINDMARSH, a citizen of the United States, and resident of Lincoln, in the county of Lancaster and State of Nebraska, have invented certain new and useful Improvements in Fence-Posts, of which the following is a specification.

My invention relates to the class of metal fence posts that are placed in position by driving, and my object is to provide a simple construction that obviates the objectionable features heretofore embodied in the round tapered metal fence post.

To obtain the maximum of efficiency from the minimum amount of metal in a driven post it is not only necessary to have strength, good anchorage and good facing to steady the post, but easy driving, so that the top of the post will not buckle when being driven.

All round tapered posts have a larger diameter at their lower point; consequently, when driven will cut a larger section of soil than can freely enter the smaller diameter of the post above.

As a result, the post continues to drive harder as it enters farther into the ground, the operator naturally using more force as the post resists, resulting in the top of the post becoming bent and buckled under the heavy blow of the driving hammer.

By making the bottom of the post in U shape, there is very little resistance to driving, in fact nothing but the thin edge of the metal, there being no packing of the soil

until the post has entered the ground to the point of the beginning of the round portion. The soil will begin to pack at this point, and the few inches of farther driving will pack the soil in the U near the ground line, making the post steady by filling out the vacancy which is so objectionable in the round tapered post.

This vacancy occurs in a round tapered post, due to the fact that a smaller diameter of the post occupies a space of a size to accommodate the larger diameter of the post at the lower end—that is, the end which first enters the ground. Furthermore, while this U-shaped bottom will drive easily, it will not pull up easy, as the

friction and packing of the soil inside of the U causes the U to retain the soil when being pulled up.

The invention will be more readily understood by reference to the accompanying drawings, wherein—

Figure 1 is a perspective view of the post as I contemplate forming it;

Fig. 2 is an enlarged perspective view of the lower end of the post;

Fig. 3 is a section on the line 3—3 of Fig. 60 2, and

Fig. 4 is a section on the line 4—4 of Fig. 2.

The post is provided at its upper end with a round tapered portion 10, and at its lower end with a U-shaped slightly tapered portion 11. It is intended, when the post is in the ground, that it shall be seated, as shown in Fig. 1, *i.e.*, with the U-shaped portion entirely beneath the surface of the ground, as indicated at 12. The post may be formed from the same blank as is used in forming the ordinary tapered tubular post, the mechanism employed, however, being so arranged that the blank is left U-shaped at its lower end.

Such posts are intended to be driven in distinction from such posts which are located in a hole in the ground and the earth filled in therearound. By making the bottom of the post in U-shape, the driving resistance is very small, there being no tendency of the soil to pack. However, as the post has entered the ground to nearly the point indicated in Fig. 1, the soil will begin to pack in the contracted portion thereof, the last few inches of driving being relatively hard. This serves to force the soil down and outward and to fill out any vacancy around the post at the point where it enters the ground. Not only is the driving easy, but a series of tests have demonstrated that the pulling resistance is great, in fact several times greater than that of a round, tapered post. This presents the ideal combination, that is, easy driving and hard pulling.

Obviously the exact form of the device may be varied, and such variations as are within the scope of my claims I consider within the spirit of my invention.

I claim:

1. A fence post, consisting of a tapered blank bent into tubular form at the point

above the ground-line and of U-shape at the point beneath the ground, substantially as described.

2. A fence post of tubular form at its upper end and of U-shape at its lower end, said post being so constructed as to permit of its being driven into the ground to a point at which the U-shaped portion is entirely be-

neath the surface of the ground, substantially as described.

Signed at Chicago, Illinois, this 21st day of October, 1915.

PERCY J. HINDMARSH.
